CLAIM

We claim the ornamental design for a bridge piece, as shown
and described.

DESCRIPTION

FIG. 1 is a front, right, top perspective view of a bridge
piece;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines immediately adjacent the shaded areas
represent the bounds of the claimed design, while all other
broken lines are directed to environment and are for illus-
trative purposes only; the broken lines form no part of the
claimed design.
